UNITED STATES PATENT OFFICE.

HOMER C. LA BATT, OF CHICAGO, ILLINOIS, ASSIGNOR TO WILLIAM J. HERRICK, OF CHICAGO, ILLINOIS.

SHEET-FEEDING MACHINE.

968,062.

Specification of Letters Patent. Patented Aug. 23, 1910.

Application filed July 10, 1902, Serial No. 115,014. Renewed January 10, 1910. Serial No. 537,335.

To all whom it may concern:

Be it known that I, HOMER C. LA BATT, a citizen of the United States, residing at Chicago, in the county of Cook and State 5 of Illinois, have invented certain new and useful Improvements in Sheet-Feeding Machines, of which the following is a specification.

This invention relates to machines to successively feed sheets of paper one at a time 10 from a pile or stack to printing, ruling, folding, and like machines.

The object of the invention is to provide a novel and improved machine of this class 15 in respect to the organization and construction of various of its features, and the invention consists in various constructions and organizations of parts, as fully described and claimed herein.

In order that the various features of my 20 invention may be fully understood, I will first describe the same with reference to the accompanying drawings, and afterward point out the novelty thereof in the annexed 25 claims.

In the accompanying drawings, in which the same reference letters refer to similar parts throughout the several views—Figure 1 is a top plan view of a sheet feeding machine embodying my improvements; Fig. 2 is a side elevation thereof on the side at 30 which power is applied, certain of the parts being shown as broken away; Fig. 3 is a sectional elevation of the same on the line 3 of Fig. 1; Figs. 4, 5, 6, and 7 are detail 35 views, partly in section and partly in side elevation, showing the relative positions of certain of the parts in the various positions of one of the feed-heads of the front group 40 of feeding devices. Fig. 8 is a detail view of gearing employed for the bucklers or pick-ups; Fig. 9 is a top view of one of the bucklers of the rear group of feeding devices, certain of the parts being shown as 45 broken away; Fig. 10 is a bottom view of the parts of Fig. 9; Fig. 11 is a front elevation of the parts of Fig. 9; Fig. 12 is a side elevation of the parts of Fig. 9; Fig. 13 is a detail sectional view on the line 13 of 50 Fig. 9; Fig. 14 is a detail sectional view on the line 14 of Fig. 13; Fig. 15 is a detail

view in elevation of certain of the parts, showing the same in a different position from that of Fig. 12; Fig. 16 is a side elevation of one of the feed-heads of the front 55 group of feeding devices, the supporting bar thereof being shown in section; Fig. 17 is a sectional view on the line 17 of Fig. 16; Fig. 18 is a detail view showing the construction of the foot of the rear buckler; 60 Fig. 19 is a detail view and shows the construction of the feet of the feed-heads of the front group of feeding devices; Figs. 20 and 21 are side views of the disks forming the laminations of the foot of Fig. 18; Figs. 65 22 and 23 are side views of the plates forming the laminations of the foot of Fig. 19; Fig. 24 is a sectional view showing the construction of a clutch mechanism that may be employed, the view being taken on the 70 line 24 of Fig. 25; Fig. 25 is a detail view of certain of the parts of Fig. 24, the view being taken on the line 25 of Fig. 24; Fig. 26 is a detail view in elevation of certain 75 of the parts of Fig. 24; Fig. 27 is a detail view of the catch of Fig. 24 detached; and Fig. 28 is a perspective view of the pin of Fig. 24.

The stack or pile of sheets S to be fed to the printing press, folder, or other machine, 80 is positioned upon an adjustable table T, which is positioned to keep the top sheet within operative relation to the feed devices, and which may be automatically adjusted, as hereinafter set forth. 85

The paper table is mounted in a suitable supporting frame A, which forms the base or support upon which the various members of the machine are carried. The frame is provided at its front with journal boxes in 90 which a suitable main shaft S' has its bearings, the shaft being provided with a suitable spur-wheel s by which power is transmitted to it from any suitable source. In the practical operation of the machine, I 95 prefer to take the power from the machine with which the feeder is associated, and for this purpose I may employ any suitable intermediate connections to transmit power to the main shaft from the associated 100 machine.

A through shaft S² is suitably mounted

in bearings, in the rear of and parallel with the main shaft. At one side of the machine, here shown on the side opposite to that on which power is applied, a longitudinal shaft S^3 is mounted in bearings s^1 and s^2 , which preferably are respectively near the shafts S' and S^2 . The rear end of the shaft S^3 extends approximately to the rear of the machine, and is provided with a key-way or groove s^3 , all as shown in Fig. 1, for a purpose to be hereinafter described. The main shaft S' is provided with a worm or screw-gear s^4 , which meshes with a worm-wheel s^5 on the shaft S^3 , to rotate the latter. The shaft S^3 is also provided with a spiral gear s^6 , which engages a corresponding gear s^7 on the through-shaft S^2 , to rotate the latter in the direction of the arrow in Fig. 2. In practice the shaft S^3 is given a single revolution to each eleven revolutions of the main-shaft, the latter having the speed of the folder or other associated machine, and revolving rapidly to furnish a quick feed-off of the sheets as hereinafter described. The spiral gears drive the shaft S^2 at the same speed as the shaft S^3 .

In the operation of the machine, the initial separation of the top sheet from the pile or stack occurs at the rear, and consequently I shall first describe the organization of the parts that accomplish this function.

A pair of guide rods A' , one on each side of the machine, extends rearwardly from the risers a' of the frame, and forms the support for an adjustable carriage, which supports the devices employed at the rear end of the pile of sheets. This carriage comprises opposite sleeves c , sliding on the rods A' and locked thereon by means of set screws c' , and a pair of cross-rods c^2 and c^3 , which are mounted at their ends in the sleeves. The front rod c^2 is adapted to rotate in its bearings as hereinafter described, but the rear rod c^3 does not rotate. The adjustability of this carriage upon its guides permits the devices carried thereby to be set at any desired point over the greater area of the paper table, whereby the machine is adapted to operate upon sheets of different sizes.

The rear carriage supports a pair of bucklers or pick-ups, shown in detail in Figs. 9 to 15, which are adapted to operate upon the rear or side edges of the sheets, and raise the top sheet from the pile for the initial separation. Each buckler comprises a carrier E , which is in the shape of a block, having lateral ears provided with openings for the cross-rods c^2 and c^3 , and adapted to slide longitudinally upon the cross-rods, being held at any desired point of adjustment, according to the length of the sheets, by means of a suitable set screw e , adapted to bear against the stationary rod c^3 . Each

block is provided on one of its sides with an undercut guide or way e' , in which a rectangular plate e^2 , having correspondingly beveled edges, is adapted to be moved for vertical adjustment. The plate e^2 is provided at its lower end with a segmental plate or web e^3 , and at its top with a wing or offset portion e^4 , which is provided to rotatably receive a suitable screw-rod e^5 carried thereby.

The screw-rod is adapted to have a threaded connection with a bore in the associated block E , in which it is adapted to be rotated by means of a suitable handle e^6 , to adjust the plate e^2 up or down in its guide or way, the engagement of the wing e^4 and the screw e^5 being such as to carry the plate with it as the screw moves up or down in its bearing. The web e^3 supports a bracket consisting of a plate and a leg; the plate e^7 is segmental, and is adjustably mounted upon the web by means of a set-screw e^8 in the latter passing through a slot e^9 in the former, as shown in Fig. 10. The bracket-leg e^{10} is located at the inner end of the plate e^7 , and is curved downwardly and inwardly, as shown in Figs. 10 and 12, with its free end terminating in a bearing e^{12} , in which a vertical shaft e^{13} is rotatably mounted. This shaft extends upwardly through a channel in the associated block E , and is provided with a key-way e^{14} , which is adapted to receive a spline or feather on the hub of a spiral-gear e^{15} . The gear e^{15} is located in a recess provided in the under face of the block E , and is held in place by a plate e^{16} , which closes the recess, as shown in Fig. 10. The shaft e^{13} may therefore be moved up or down through the block, by means of the adjustment provided by the screw-shaft e^5 and intermediate parts, and maintains operative relations with the gear e^{15} . The rotating shaft c^2 is provided with a spiral gear c^5 , which meshes with the gear e^{15} . The gear c^5 is provided with a feather to enter the groove or way c^6 of the shaft c^2 , and it is moved along the shaft, when the corresponding block E is shifted longitudinally thereof, by reason of the fact that it is located in a recess provided in the lateral ear of the block that engages the shaft c^2 , as shown in Figs. 10 and 11.

The shaft e^{13} is provided near its bottom with a miter-gear wheel e^{17} , which meshes with a corresponding gear-wheel e^{18} on the inner end of a longitudinally disposed shaft e^{19} , which is mounted in suitable bearings on the bracket-plate e^7 just above the bracket-arm e^{10} . The shaft e^{19} extends forwardly beyond the block E , and carries a rotating pad or pick-up P . The shaft e^{19} is provided with a collar e^{20} to hold it in place, and on its inner end is mounted an adjustable buckler sleeve e^{21} , which is held to rotate therewith in its adjusted position thereon by a set-

130

screw e^{22} . An arm e^{23} is integral with the sleeve, and carries a hub e^{24} at its outer end, which is provided with a central channel to receive a movable pin e^{25} , to one end of which is secured a thumb-piece e^{26} by means of a retaining pin e^{27} . A sleeve e^{28} is loosely mounted on the pin e^{27} next to the hub, and carries an arm e^{29} , upon the outer end of which a yoke e^{30} is provided for the pad or sole P of the buckler. The sleeve e^{28} is provided with a detent e^{31} , which is adapted to be forced against a stop or pin e^{32} extending laterally from the arm e^{23} , the sleeve being held to position by means of a spring e^{33} , which is secured to the yoke e^{30} at one end and at the other end to a collar e^{34} fast on the pin e^{25} . A coil spring e^{35} surrounds the pin e^{25} between the sleeve e^{28} and collar e^{34} , and serves to hold the parts in the position of Fig. 13, with the pin e^{36} of the disk e^{26} in engagement with one of the holes e^{37} of the hub. By this construction the pad is pivotally mounted upon the pin e^{25} , and is yieldingly held by means of the spring e^{33} , the detent preventing the spring from throwing the pad out of operative position. The tension of the spring e^{33} may be adjusted by withdrawing the pin e^{36} from engagement with the hole of the hub, and turning the disk and pin e^{25} to adjust the spring e^{33} , when the spring e^{35} will again lock the parts in position, as in Fig. 13.

The pad P is a laminated structure composed of soft rubber disks e^{38} , assembled upon a pin e^{40} mounted in the ends of the yoke. By means of this construction the yielding edges of the rubber-disks, when they engage the paper, will tend to flatten out, as upon the dotted line Fig. 21; so that instead of engaging the paper at only a single point of their peripheries, they will furnish an extended contact surface. As the shaft e^{19} revolves, the pad is carried around the axis of the shaft as a center of rotation in the direction of the arrow of Fig. 11, and the pad yieldingly engages the top sheet at its rear to buckle the latter against suitable holders F, which are hereinafter described, to produce the initial separation. The pads P may be composed of alternate disks of metal or fibrous material e^{38} and of rubber e^{39} .

The pads of the bucklers may be adjusted angularly with relation to the shaft c^2 , so as to pick up the paper from any angle at its sides or ends, by loosening the nut e^8 and adjusting the bracket-plate e^7 thereon, the plate and its supporting web being on the segment of a circle whose center is the shaft e^{18} , so that the parts remain in operative relation at any point of the adjustment. The pads are preferably set at an angle of twelve or fifteen degrees to the shaft c^2 , such as shown in Figs. 9 and 10. As the pads rotate they buckle the top sheet against the

feet f' of the holders F, and allow inflowing currents of air to pass beneath the sheet.

The holders F are carried on the shaft c^3 , and are adjustably secured thereon by set-screws f, so that they may be set to agree with the different adjustments of the bucklers. They are provided with feet f', against which the sheets are buckled, and with lips f², which hold the rear edges of the sheet after it has been drawn forward by the front feeding-devices for the preliminary separation, and prevent the air blast from disturbing the sheet. The holders are readily attachable to and detachable from the rod c^3 by means of the half-collars with which they are provided as shown.

A holding foot is preferably associated with each pick-up or pad, and is adapted to be lifted from the sheet during the interval that the pad is acting thereon. For this purpose I secure a stub e^{41} in the bracket-arm e^{10} , upon which is mounted a loose sleeve e^{42} , having a forwardly projecting arm e^{43} carrying a presser-foot e^{44} , and a rearwardly extending arm e^{45} having an anti-friction roller e^{46} adapted to be acted upon by a cam e^{47} on the lower end of the shaft e^{13} . A coil spring e^{48} is mounted on the stub, and at one end engages the sleeve e^{42} and at the other engages an adjusting button or knob e^{49} , which is capable of slight longitudinal movement on the stub, against the force of the spring, to disengage a pin e^{50} on the stub, which enters recesses e^{51} on the front flange of the knob.

The shaft c^2 is rotated from the shaft S^3 . The latter is provided with a spiral-gear s^9 , which engages and drives a corresponding gear c^4 on a sleeve c^5 loose on the shaft c^3 . The gear s^9 is provided with a feather or spline to engage the groove s^8 of the shaft S^3 , and is moved along its shaft by means of inwardly projecting portions c^6 of the carriage, which embrace the wheel, as the carriage is adjusted along its guides A' for sheets of different sizes. The rotation of the sleeve c^5 is transmitted to the shaft c^2 by means of the elliptical spur-gear c^7 , which engages a corresponding gear c^8 , secured upon the shaft c^2 . By this means the rotation of the shaft c^2 is given a varying speed, the parts being so adjusted that the slow speed of the shaft shall occur while the bucklers that are driven thereby are in engagement with the paper, and the accelerated speed shall occur while the bucklers are revolving around their centers out of engagement with the paper. This arrangement of gears is shown in detail in Fig. 8.

The stationary rod c^3 may be conveniently employed as a support for brackets D for the air-supply devices, and which may be adjusted along the rod to the required position and held by set-screws d. The brackets are provided with split collars d' to receive the

1 nozzles d^2 , whereby the latter may be adjusted vertically and radially. The air supply is furnished from any suitable source, as by a tube d^3 on the risers a' , and provided with a plurality of valves d^4 , whereby air may be taken at any desired point. The valves connect with the nozzles by suitable piping d^5 , and the tube is connected to any suitable source of air supply. The nozzles are adjusted to inject the air between the top sheet and the pile at points in proximity to the bucklers, so that after the bucklers have picked up the edge or corners of the sheet, the air is supplied beneath the sheet to lubricate it and loosen it from the pile throughout its surface.

2 When the bucklers have operated to raise the corners of the top sheet against the feet f' of the holders, the sheet is fed forward by the front feeding devices sufficiently to draw the rear edge free of the feet but not beyond the action of the lips f^2 , which engage the sheet until the feeding-off mechanism, hereinafter described, ejects it entirely from the machine.

3 I will now proceed to describe the front feeding devices, which draw the sheets forward from beneath the feet f' and supply them to the feed-off devices.

4 The bearing blocks, in which the shaft S' is journaled, are provided with rearwardly projecting stubs or guides a , which support sleeves a^2 , forming carriers for the feed-heads constituting the front members of the sheet-feeding devices. Each sleeve is provided with an upright or standard a^3 , upon which is slidably mounted a block a^4 , the blocks being held in their lower positions by means of coil springs a^5 , interposed between the blocks and suitable washers or plates a^6 on the ends of the uprights. The blocks carry a square rod a^7 , upon which the heads B are adjustably carried, being held in position thereon by set screws b . The carriers a^2 of the heads are reciprocated on their guides a by means of links a^8 which are pivotally attached at one end to ears a^9 on the carriers and at their opposite ends to disks s^8 on the ends of the through-shaft S^2 .

5 The blocks a^4 are raised on their uprights against the springs a^5 , by means of arms a^{10} , which are pivoted at a^{12} to the risers or standards a' on the frame in the rear of the disks s^8 . The arms are provided with anti-friction wheels a^{13} , which are in the paths of suitable cam portions of the disks s^8 to lift the parts against the stress of the springs. The free ends of the arms are provided with anti-friction rollers a^{14} that bear against the under faces of ledges or projections a^{15} on the blocks a^4 , as shown in Fig. 2.

6 Each feed-head comprises a block b^2 , which is provided with a square opening to receive the rod a^7 , and is adjusted on the rod according to the position required, which of

70 course may vary with the width of the sheets. The block carries a screw-rod b^3 , provided with a handle b^4 , and which engages a threaded collar b^5 , which is attached to a cross-piece b^6 . The cross-piece is rigidly secured at its ends to opposite plates b^7 , which are adapted to move in ways or guides on opposite faces of the block, being raised or lowered by rotating the screw-rod. Each plate is provided with top and bottom offset ears b^8 and b^9 , which are perforated for the reception of the stem b^{10} of a foot b^{12} . The stem passes through the opening of the lower ear, where it is provided with a cross-pin b^{13} , and it is then somewhat reduced in diameter and extended through the opening of the upper ear. The bore of the upper ear is threaded for engagement with the external thread of a hollow screw-bolt b^{14} , provided with a knurled head b^{15} , and adapted to loosely receive the upper end of the stem. The screw bolt bears on a coil spring b^{16} , which surrounds the stem and with its lower end bearing on a washer b^{17} on the pin of the stem, whereby the stem is yieldingly 80 mounted in the plate and the pressure of the spring may be varied. The lock-nut b^{18} holds the bolt in adjusted position. The sole or bearing surface of each foot b^{12} is composed of a laminated structure made up 90 of alternate plates or disks of rubber b^{19} and wood or other fibrous material b^{20} , secured together by suitable parts, as shown in Figs. 19, 22 and 23. The rubber plates are larger than the others, and form the contact surfaces, the other plates providing small air gaps intermediate the rubber plates. Each foot is provided with a guide stem b^{21} , which enters a suitable opening in the plate b^9 .

95 From a consideration of the foregoing it 105 is apparent that the feed-heads and bucklers may be adjusted upon their respective carriers to accommodate any width of paper that the machine may receive, and that the bucklers may be set nearer to or farther 110 from the heads according to the length of the sheets.

10 The feeding-off mechanism is located at the front of the machine, and comprises opposing disks having intermittent co-operation. The shaft S' is provided at intervals 115 with disks s^{14} , which are adapted to co-operate with disks s^{15} , to feed-off the sheet or eject it from the feeder to the associated machine after it has been preliminarily separated from the pile. The disks s^{15} are mounted on a shaft s^{16} , that is loosely journaled in a pair of swinging arms s^{17} , pivoted to the frame at s^{18} and provided at their rear ends with anti-friction rollers s^{19} , that are 120 adapted to be engaged by cams s^{20} on the shaft S^2 , as shown in Fig. 3. The cams operate the arms when the feed-feet are raised from the paper, and the opposing disks 125 co-operate to feed the sheet clear of the ma- 130

chine, the length of coöperation being of course dependent upon the length of the cams s^{20} .

The paper table T runs in suitable guides in the frame, and is raised and lowered by suitable screw-shafts t^2 , which are connected together for simultaneous operation by a cross-shaft t^3 and miter-gears t^4 . An angle-lever t^5 is pivoted upon one side of the frame, and its longitudinal leg is provided with a pawl t^6 , adapted to take into a ratchet-wheel t^7 on the shaft t^8 , being held yieldingly to its work by a spring t^9 . The vertical leg of the angle lever is provided with an anti-friction roller t^9 , adapted to be drawn against the periphery of a disk t^{10} on the shaft S^2 by a suitable spring t^{12} . The longitudinal leg of the angle lever is provided with a catch t^{13} , adapted to receive a latch-lever t^{14} , which normally engages therewith and holds the roller t^9 against the force of the spring t^{12} and out of operative relation with the depression t^{15} formed in the periphery of the disk. It is obvious that when the latch is disengaged from the lever, the spring t^{12} will draw the roller t^9 against the edge of the disk t^{10} and into the depression, whereby the pawl is drawn up over one or more of the ratchet-teeth, and when the roller rides out of the depression and is returned by the enlarged periphery of the disk to the position of Fig. 3, the pawl will be forced down to turn the shaft t^3 to raise the table. The unshipping of the latch is preferably accomplished by means controlled by the height of the paper on the table. The latch is secured upon a rock-shaft t^{16} , one end of which bears in the end frame of the machine and the other in a bracket t^{20} , which is secured by a set-screw upon the air-tube at the center of the machine. The rock-shaft is provided with a weighted arm t^{17} , which tends to throw the face end of the latch t^{14} into engagement with the catch t^{13} , and the arm is provided with a depending lug or pin t^{18} . A bell-crank lever t^{19} is pivoted in the lower end of the bracket t^{20} , at about the middle of the machine, the longer leg of the lever being projected into the path of the paper at the front edge of the machine and provided with an anti-friction roller t^{21} adapted to rest thereon. The opposite or upper end of the lever t^{19} projects behind the pin t^{18} , and is provided with an adjustable set-screw t^{22} , adapted to be locked in position by a set-nut t^{23} , and adjusted so as not to contact with the pin t^{18} when the roller t^{21} is held by the paper at what may conveniently be termed normal position. When, however, the paper pile is reduced by the successive feeding of the sheets, or otherwise, to a height below normal position, the front end of the lever t^{19} drops and causes the screw t^{22} to engage the lug t^{18} to rock the shaft t^{16} to move the latch t^{14} from its catch

t^{13} , whereby the spring t^{12} draws the lever t^5 forward to effect the rotation of the shaft t^3 as above described.

To provide a stopping and starting mechanism, I mount a suitable handle H in any convenient location upon the machine, as in a guide h upon the bracket t^{20} , and extending forwardly to engage a suitable rocker-arm h' attached to a rock-shaft h^2 , which is supported in suitable brackets on the frame. A support shaft h^3 extends across the machine, parallel with and below the rock-shaft, to support the latter at the center of the machine by any suitable interposed block, provided on the frame to guide a movable stem h^4 , which has suitable sliding engagement with a forwardly projecting arm h^5 on the rock-shaft h^2 . The stem h^4 carries an adjustable collar h^6 , which is locked thereon by a set-screw h^7 , and two coil springs h^8 and h^9 are provided, one above and the other below the collar, and bearing respectively upon the upper and lower ears. By this construction the stem is balanced in position, and when moved in either direction will return to its normal central position. The stem carries a latch h^{12} at its lower end, which is adapted to throw a suitable clutch, whereby the machine may be started and stopped.

The clutch is shown in detail in Figs. 24 to 28, and comprises a disk h^{14} , which is suitably keyed to the main shaft S' , and a driving member h^{15} , which is loosely mounted on the shaft and is constantly rotated by any suitable means, as the gear wheel s . The disk h^{14} is provided on its face with the lateral flange h^{16} , which is cut away or recessed at any suitable point to form a seat h^{17} , having one wall or face abrupt for its full depth, as at h^{18} , and the other abrupt for a portion of its depth and then developing into an incline h^{19} . The driving member h^{15} is in the form of a sleeve, and is provided on its inner face with a recess h^{20} , in which a pin h^{21} is seated. The pin h^{21} is provided with a pocket h^{22} in its rear end, which receives a protracting spring h^{23} , bearing between the base of the pocket and recess to throw the pin h^{21} . The pin is provided on its outer face with a stop or ledge h^{24} , which fits in a corresponding cut-away of the recess h^{20} , and holds the pin from turning as well as limiting its inward movement. The stop is formed with an angular shoulder h^{25} on its front end, and is provided with a cross-cut h^{26} , forming a recess. The sleeve h^{15} is provided with a standard h^{27} , having a bracket h^{28} at its outer end, against which one end of a coil spring h^{29} bears, its opposite end bearing upon a catch h^{30} , provided with a guide-pin h^{31} , about which the spring is coiled. The catch is provided with a lug h^{32} on its bottom having an inclined or rounded face h^{33} , and with a lateral shoulder h^{34} .

With the parts in the position of Fig. 24, the members of the clutch are disengaged, and as the sleeve h^{15} revolves the projection or shoulder h^{34} does not contact with the latch h^{12} . If now the stem h^6 be raised, by moving the handle H in the appropriate direction, it will project an eccentric face h^{35} , on the upper surface of the latch, into the path of the shoulder h^{34} , whereby the catch h^{30} is raised against its spring from engagement with the recess h^{26} , and the pin h^{21} is projected by its spring against the flange h^{16} and passes down the incline into the seat h^{17} as the sleeve rotates to lock the sleeve 10 and disk together to rotate the shaft S' . When it is desired to open the clutch, the handle is oppositely moved to lower the stem h^6 , whereby the lateral cam h^{36} on the lower portion of the latch h^{12} is thrown into the path of the angular shoulder h^{25} , whereby the pin h^{21} is protracted until the lug h^{32} engages its seat h^{26} . The pin is then held in retracted position, and the parts of the clutch are disconnected.

From a consideration of the above disclosure it is apparent that the initial separation of the top sheet from the pile is effected at or near its rear corners, and that the buckling or arching thereof occurs during 25 the slower movement of the bucklers provided by the elliptical gear, at which time the feed-heads are in the position of Fig. 6. At the moment after the bucklers have performed their function, the heads are projected to the position of Fig. 7, to deliver the sheet to the feeding-off mechanism. When the feed-heads have projected the sheet into the bight of the feed-off mechanism, the heads rise to the position of Fig. 4, 30 and the disks s^{15} are raised to coöperate momentarily with the disks s^{16} to eject the sheet. As the heads rise, the bucklers again become operative and buckle the next sheet, while the heads are being retracted to the 35 position of Fig. 6, and the feed-off becomes 40 inoperative.

By means of the adjustments provided for the bucklers and heads, the machine may operate on different sizes of sheets. All the 45 operating devices for the rear portions of the sheet being mounted on a single carriage, the machine can be readily adjusted to the required size.

The pile of sheets is kept automatically 55 in operative relation with respect to the bucklers and heads, and the machine may be quickly started and stopped by the handle, which may be placed in easy reach of the attendant.

It is to be understood that the shaft S' 60 may be driven by elliptical gears if desired, in order to give the feed-heads a slow forward movement and a quick return.

I make no claim in this application to the 65 clutch herein shown; the same has been

divided out of this application and made the subject-matter of a divisional application filed Jan. 26, 1903, bearing Serial Number 140,530 and patented August 31, 1909, Number 932,558.

Having described my invention, what I claim as new and desire to secure by Letters Patent is—

1. In a sheet-feeding machine, the combination with a paper-table, of front feeding devices adjustable with respect to the width of the table, a carriage adjustable lengthwise of the table, and a rotating buckler on the carriage and moving at variable speed. 70

2. In a sheet-feeding machine, the combination with a paper-table, of front feeding devices adjustable with respect to the width of the table, a carriage adjustable lengthwise of the table, and bucklers rotating at a variable speed and coöperating holders adjustable on the carriage transversely of the 80 table. 85

3. In a sheet-feeding machine, the combination with a paper-table, of front feeding devices adjustable with respect to the width 90 of the table, a carriage adjustable lengthwise of the table, air-nozzles adjustable on the carriage, and bucklers rotating at a variable speed and holders having independent adjustment on the carriage across the 95 table.

4. In a sheet-feeding machine, the combination with a paper-table having rearwardly extending guides, and front-feeding devices, of a carriage comprising sleeves movable on 100 the guides and cross-rods on the sleeves, and rotatable bucklers adjustable on the rods and driven by connections with one of the rods.

5. In a sheet-feeding machine, the combination with a paper-table having rearwardly 105 extending guides, and front-feeding devices, of a carriage comprising sleeves movable on the guides and cross-rods on the sleeves, and bucklers and holders adjustable independently on the rods. 110

6. In a sheet-feeding machine, the combination with a paper-table having rearwardly extending guides, and front-feeding devices, of a carriage comprising sleeves movable on 115 the guides and cross-rods on the sleeves, means to rotate one of said rods, rotatable bucklers adjustable on the rods, and means to operate the bucklers from the rotating rod. 120

7. In a sheet-feeding machine, the combination with a paper-table having rearwardly extending guides, and front-feeding devices, of a carriage comprising sleeves movable on the guides and cross-rods on the sleeves, means to rotate one of said rods, blocks on the rods, rotating pads on the blocks, and gearing between the pads and rotating rod. 125

8. In a sheet-feeding machine, the combination with a paper-table having rearwardly 130

- extending guides, and front-feeding devices, of a carriage comprising sleeves movable on the guides and cross-rods on the sleeves, means to rotate one of said rods, a gear wheel splined on said rotating rod, a block adjustable on the rods and moving said gear wheel on its rod, a pad mounted to rotate on said block, and means to drive the pad from the said gear wheel.
10. In a sheet-feeding machine, the combination with a paper-table having rearwardly extending guides, and front-feeding devices, of a carriage comprising sleeves movable on the guides and cross-rods on the sleeves, means to rotate one of said rods, gear-wheels splined on said rotating rod, blocks adjustable on the rods and each provided with means to move one of the gear-wheels, a pad rotatably mounted on said block, and gears on the block between the pad and wheel thereon.
10. In a sheet-feeding machine, the combination with a paper-table having rearwardly extending guides, and front-feeding devices, of a carriage comprising sleeves movable on the guides and cross-rods on the sleeves, means to rotate one of said rods, gear-wheels splined on said rotating rod, blocks adjustable on the rods and each provided with means to move one of the gear-wheels, a shaft on each block driven by one of the gear wheels, a second rotatable shaft on each block and having a pad, and miter-gears between the shafts of the block.
11. In a sheet-feeding machine, the combination with a paper-table having rearwardly extending guides, and front-feeding devices, of a carriage comprising sleeves movable on the guides and cross-rods on the sleeves, means to rotate one of said rods, gear-wheels splined on said rotating rod, blocks adjustable on the rods and each provided with means to move one of the gear-wheels, a vertical shaft on each block, a gear-wheel on the vertical shaft driven by one of the first gear-wheels, a horizontal shaft on each block carrying a rotating buckler, miter-gears between the shafts of the block, a cam on the lower end of the vertical shaft, and a presser foot on the block coöperating with the cam.
12. In a sheet-feeding machine, the combination with a frame having a main-shaft, a paper-table on the frame, and means driven by the main-shaft to buckle the paper at the rear, of a front-feed comprising carriers reciprocating horizontally on the frame, blocks sliding on the carriers toward and from the table, and horizontally adjustable feed-heads carried by said blocks.
13. In a sheet-feeding machine, the combination with a frame having a main-shaft, a paper-table on the frame, and means driven by the main-shaft to buckle the paper at the rear, of horizontal guides on the frame, carriers reciprocating on the guides, blocks vertically movable on the carriers, a rod carried by the blocks, and feed-heads adjustable on the rod.
14. In a sheet feeding machine, the combination with a paper table and means to buckle the sheets near their rear corners, of a front feed comprising a vertically moving reciprocating rod provided with blocks adjustable thereon, and feed pads carried by the blocks.
15. In a sheet feeding machine, the combination with a frame having a main shaft, a paper table on the frame, and means driven by the main shaft to buckle the paper at the rear, of a front feed comprising carriers reciprocating on the frame, blocks on the carriers, rods on the blocks, and feed pads on the rods.
16. In a sheet feeding machine, the combination with a paper table and means to buckle the sheets near the rear, of a front feed comprising a rod reciprocating on the frame, blocks adjustable on the rod, plates adjustable on the blocks, and stems carrying rubber pads yieldingly mounted on the plates.
17. In a sheet-feeding machine, the combination with a frame having a rotating shaft, a paper table on the frame, and means to initially separate the top sheet of the paper-stack, of horizontal guides near the front of the frame, carriers on the guides, standards on the carriers, blocks movable on the standards and carrying feed-heads, connections between the shaft and carriers to reciprocate the latter on the guides, and connections between the shaft and blocks to raise the latter.
18. In a sheet-feeding machine, the combination with a frame having a rotating shaft, a paper table on the frame, and means to initially separate the top sheet of the paper-stack, of horizontal guides near the front of the frame, carriers on the guides, standards on the carriers, blocks movable on the standards and carrying feed-heads, links connecting the carriers and shaft to reciprocate the former, arms pivoted to the frame and movably engaging the blocks, and means to rock the arms to raise the blocks.
19. In a sheet-feeding machine, the combination with a frame having a rotating shaft, a paper table on the frame, and means to initially separate the top sheet of the paper-stack, of horizontal guides near the front of the frame, carriers on the guides, standards on the carriers, blocks movable on the standards and carrying feed-heads, disks on the shaft, links between the disks and carriers, arms pivoted on the frame engaging the blocks and in the path of the disks.
20. In a sheet-feeding machine, the combination with a paper-table, and a reciprocating

- ing rod, of feed-devices adjustable thereon and having a plate, a stem movably mounted on the plate, a spring for the stem, means to adjust the tension of the spring, and a 5 pad on the stem.
21. In a sheet-feeding machine, the combination with a paper-table, and a reciprocating rod, of feed-devices adjustable thereon and having a plate, a stem movably mounted on the plate, a spring for the stem, a set-screw for the spring, a lock-nut for the screw, and a pad on the stem.
22. In a sheet-feeding machine, the combination with a paper-table, and a reciprocating rod, of feed-devices adjustable thereon and comprising a block, a plate adjustable on the block, a stem having a pad and movably mounted on the plate, a spring for the stem, and means to adjust the force of the spring.
23. In a sheet-feeding machine, the combination with a paper-table, and a reciprocating rod, of feed-devices adjustable thereon and comprising a block having a way or guide, a plate in the guide, a screw-rod on one of the parts having threaded connection with the other, and a foot having a stem yieldingly mounted on the plate.
24. In a sheet-feeding machine, the combination with a paper-table, and a reciprocating rod, of feed-devices adjustable thereon and comprising a block having guides or ways on opposite sides, plates in the guides, a union for the plates, a screw-rod connected with the block and having threaded connection with the union, and stems each carrying a foot and yieldingly mounted in one of the plates.
25. In a sheet-feeding machine, the combination with a paper-table and front-feed devices, of a rear buckler having a rotating shaft carrying a laminated pad movable into and out of engagement with the pile of sheets by the rotation of the shaft.
26. In a sheet-feeding machine, the combination with a paper-table and front-feed devices, of a rear buckler comprising a block, a horizontal rotating shaft on the block, a sleeve loose on the shaft, an arm on the sleeve carrying a pad, a spring between the sleeve and shaft, and a stop to limit the movement of the sleeve.
27. In a sheet-feeding machine, the combination with a paper-table and front-feed devices, of a rear buckler comprising a block, a bracket on the block, and a buckling-pad on the bracket, said bracket being adjustable to vary the angle of attack of the pad.
28. In a sheet-feeding machine, the combination with a paper-table and front-feed devices, of a rear buckler comprising a block having a segmental web, a bracket adjustable on the web, and a buckling-pad on the bracket.
29. In a sheet-feeding machine, the combination with a paper-table and front-feed devices, of a rear buckler comprising a block having a segmental web, a bracket having a slot and pin connection with the web, and a buckling-pad on the bracket.
30. In a sheet-feeding machine, the combination with a paper-table and front-feed devices, of a rear buckler comprising a block, a plate vertically adjustable on the block, and a positively rotated buckler-pad carried by the plate.
31. In a sheet-feeding machine, the combination with a paper-table and front-feed devices, of a rear buckler comprising a block, a plate vertically adjustable on the block, a 80 bracket carried by the plate, a driven shaft mounted in the bracket, and a rotating buckler-pad driven by the shaft.
32. In a sheet-feeding machine, the combination with a paper-table and front-feed devices, of a rear buckler comprising a block, a plate adjustable on the block, a bracket on the plate, a vertical driven shaft on the bracket, a horizontal shaft on the bracket and carrying a rotating buckler-pad, gears 90 connecting the shafts, and means for adjustably uniting the plate and bracket on a segment of a circle whose center is the axis of the vertical shaft.
33. In a sheet-feeding machine, a buckler 95 comprising a block having a guide or way, a plate movable in the way, a screw-shaft engaging the block and plate to adjust the latter on the former, a bracket on the lower end of the plate, a vertical shaft mounted 100 on the bracket and passing through the block, a gear in the block having sliding connection with the shaft, a longitudinal shaft on the bracket and geared to the first shaft, and a buckler-pad operated by the 105 longitudinal shaft.
34. In a buckler for sheet-feeding machines, a rotating horizontal shaft, a sleeve rotating with the shaft and having an arm, a hub at the end of the arm, a pin in the 110 hub, a sleeve loose on the pin and carrying a buckler-frame, a spring between the frame and pin, and a detent for the frame.
35. In a buckler for sheet-feeding machines, a rotating horizontal shaft, a sleeve 115 rotating with the shaft and having an arm, a hub at the end of the arm and having a series of annular holes, a pin in the hub having a head provided with a projection adapted to any one of said holes, a sleeve 120 loose on the pin and carrying a buckler-pad, a spring between the pin and pad, and a coil spring between the loose sleeve and first spring.
36. In a sheet feeding machine, the combination with front feeding devices, of rear rotating bucklers moving at a variable speed.
37. In a sheet-feeding machine, the combination with a buckler-block, a rotating buckler-pad mounted thereon, and a shaft 130

to drive the pad, of a spring-pressed holding-foot on the block, and a cam on the shaft to raise the foot.

38. In a sheet-feeding machine, the combination with a buckler-block, a rotating buckler-pad mounted thereon, and a shaft to drive the pad and provided with a cam, of a stub on the block, a sleeve on the stub, a spring for the sleeve, a foot on the sleeve, and an arm on the sleeve in the path of the cam.

39. In a sheet-feeding machine, the combination with a buckler-block, a rotating buckler-pad mounted thereon, and a shaft to drive the pad and provided with a cam, of a stub on the block, a sleeve on the stub, a coil spring on the stub secured to a collar at one end and to the sleeve at the other end, a pin on the stub to engage the collar, a foot on the sleeve, and an arm on the sleeve in the path of the cam.

40. In a sheet-feeding machine, the combination with a paper-table, and front-feeding devices, of rear bucklers, air-nozzles, and holders against which the sheets are buckled, the holders being provided with feet and lips.

41. In a sheet-feeding machine, the combination with a paper-table, and front-feeding devices, of laterally adjustable rear bucklers, adjustable air-nozzles, and laterally adjustable holders having rear feet and front lips.

42. In a sheet feeding machine, the combination with a paper table, of feed devices provided with laminated pads movable into and out of engagement with the sheets.

43. In a sheet feeding machine, the combination with a paper table, of a rear sheet separating device provided with a laminated pad movable into and out of engagement with the sheets.

44. In a sheet-feeding machine, the combination with a paper-table, screw rods to raise the table, a shaft geared to the rods and having a ratchet, and a pawl to operate the ratchet, of a lever to operate the pawl, a latch for the lever, a rock-shaft carrying the latch, a lug on the shaft, a pivoted arm whose front end rests on the paper and whose rear end is adapted to contact with the lug to rock the shaft when the front end falls below its normal position, cams to operate the lever when the latch is operated, and means to return the latch to engagement with the lever.

45. In a sheet-feeding machine, the combination with a paper-table, and sheet-separating devices, of a feeding-off mechanism comprising a main-shaft having disks, an idle auxiliary shaft located under the main shaft and having co-operating disks, arms

supporting the auxiliary shaft, and cams to raise the arms to cause the disks of the shafts to co-operate.

65

46. In a sheet-feeding machine, the combination with a paper-table, and sheet-separating devices, of a feeding-off mechanism comprising a main-shaft having disks, an idle auxiliary shaft located under the main shaft and having opposite disks, cam-arms for the auxiliary shaft, a driven shaft, and cams on the driven shaft to raise the arms.

70

47. In a sheet-feeding machine, a feed-pad movable into and out of engagement with the sheets and consisting of thin disks of rubber separated by washers of lesser diameter than the disks.

75

48. In combination with a sheet feeding machine provided with a table and front feeding devices, of rear feeding devices rotated at variable speed.

80

49. In combination with a sheet feeding machine provided with a table and front feeding devices, of rotatable rear feeding devices rotated at variable speed.

85

50. In combination with a sheet feeding machine provided with a table and front feeding devices, of rotatable bucklers, and elliptical gearing for rotating the bucklers at variable speed.

90

51. A feed-pad consisting of thin parallel sections of rubber arranged to engage and flatten out against the paper at their edges.

95

52. A feed pad consisting of thin disks of rubber fastened together transversely of the axis of the pad and adapted to engage the paper at their edges.

100

53. In a sheet feeding machine, the combination with a buckler block, of an angularly adjustable buckler pad rotatably mounted thereon, and a shaft to rotate the pad.

54. In combination with a sheet feeding machine provided with a table and front feeding devices, of rotatable sheet separators, and elliptical gearing for rotating the separators.

105

55. In a sheet feeding machine, the combination with a main shaft and front feeding devices, of a carrier, rear feeding devices mounted upon the carrier, and a shaft to actuate the rear feeding devices, and an elliptical gear connection between the main shaft and the shaft actuating the rear feeding devices.

110

115

In testimony whereof I affix my signature in presence of two witnesses.
